UNITED STATES PATENT OFFICE.

JOHN F. ROHOWITS, OF SEATTLE, WASHINGTON.

LIQUID-SOAP RESERVOIR.

984,159.

Specification of Letters Patent. Patented Feb. 14, 1911.

Application filed March 30, 1910. Serial No. 552,441.

To all whom it may concern:

Be it known that I, JOHN F. ROHOWITS, a citizen of the United States of America, and a resident of the city of Seattle, in the 5 county of King and State of Washington, have invented certain new and useful Improvements in Liquid-Soap Reservoirs, of which the following is a specification.

My invention relates to devices of the 10 above type and has for its primary object to provide a construction, particularly adapted for holding liquid soap over lavatories, wash basins and the like, which will be sanitary, the outlet valve of the reservoir being provided with actuating means of such type as 15 to obviate the necessity of the hands being employed in the operation thereof.

Other objects will be set forth as my description progresses and those features of 20 construction, arrangements and combinations of parts on which I desire protection succinctly defined in my annexed claims.

Referring to the accompanying drawing, in which like numerals of reference indicate 25 like parts throughout: Figure 1 is a side elevation of my invention, a portion of the bracket being broken away, and Fig. 2 is a fragmentary section view on enlarged scale.

Referring to the drawing by numerals of 30 reference, 1 indicates a reservoir, and 2 an outlet passage communicating therewith and controlled by an inwardly opening valve 3, carried by stem 4 having connection with a spring 5 for normally holding valve 3 on 35 its seat.

Reference numeral 6 indicates a foot operated controller for opening valve 3 against the action of spring 5, the same being preferably arranged on the floor or in proximity 40 thereto so as to be in position for convenient engagement by the foot of a person desiring the operation of the valve. Controller 6 is pivotally supported, as at 7, on a fixed bracket as shown and has connection with a bell crank lever 8 through the medium of 45 an elbow connection 9, comprising hinged links, one of which is pivoted to said controller and the other to one arm of said bell crank. Bell crank 8 is pivotally supported, as at 9', and has its other arm pivoted to a vertically movable rod 10 whose upper end portion is swiveled in a coupling 11, connected with one end of a lever 12, pivoted 50 at 12'. Lever 12 has its other end portion engaged with the enlarged lower end portion 4' of stem 4, said end portion being

preferably grooved to provide a seat for sliding engagement with the adjacent end portion of lever 12, as will be readily understood by reference to Fig. 2.

In the operation of my device, reservoir 1 can be supported in any desired manner, a convenient and particularly desirable means however, is in the form of a wall bracket 13 having a pivoted arm 14 whose pivot 14' is 65 in vertical alignment with rod 10. Arm 14 is slotted, as at 15, and receives the central portion of lever 12, the end portions of said lever depending therefrom and connected respectively with coupling 11 and valve stem 70 4 as hereinbefore described.

Outlet 2 is in the form of a suitable conduit provided in the outer end portion of arm 14, the upper end portion of such conduit extending through a boss 2', which has 75 reservoir 1 removably connected therewith as shown, and forms a seat for valve 3.

Reservoir 1 may be provided with a closure 1' of any suitable construction which will permit of the filling of the reservoir 80 with the liquid soap, as will be readily understood.

Through the medium of swivel coupling 11 and pivot 14', the arm 14 can be swung to bring the reservoir to and from a position 85 normally occupied when in use, as for example, over a wash stand or basin 16. After each operation of valve 3 through the depression of controller 6, spring 5 both reseats said valve and returns said controller to its 90 normal position, as is apparent.

Having thus described my invention, what I claim as new, and desire to secure by Letters Patent of the United States of 95 America, is:

1. A device of the character described comprising a support, a reservoir on said support provided with an outlet, a valve for the outlet of said reservoir provided with a depending stem, a spring engaged with the 100 stem of said valve tending to normally seat the latter, means on said support engaged with said stem for unseating said valve, means on a relatively fixed part for operating said first means, said last means including a vertically slideable rod, a swivel connection between said rod and said first means, and means connecting said support for swinging movement.

2. A device of the character described, 110 comprising a support, a reservoir on said support provided with an outlet, said sup-

port being provided with a chamber beneath said reservoir outlet and out of communication therewith, a valve for the outlet of said reservoir provided with a stem extending through the chamber of said support, a spring in said chamber engaged with said stem, and means on said support for operating said stem to open said valve.

3. A device of the character described, 10 comprising a reservoir provided with an outlet, means swingingly supporting said reservoir, a valve for the outlet of said res-

ervoir, and means for operating said valve including a member arranged on a relatively fixed part, and a second member on said first means having pivotal connection with said first member, permitting of its swinging with said first means. 15

Signed at Seattle, Washington this 17th day of March 1910.

JOHN F. ROHOWITS.
